UNITED STATES PATENT OFFICE.

WILLIAM A. WRIGHT, OF MASONVILLE, NEW JERSEY, ASSIGNOR OF ONE-HALF TO A. J. LAMBORN, OF PHILADELPHIA, PENNSYLVANIA.

SIGNAL-LANTERN.

No. 824,053.

Specification of Letters Patent.

Patented June 19, 1906.

Application filed January 21, 1905. Serial No. 242,102.

To all whom it may concern:

Be it known that I, WILLIAM A. WRIGHT, a citizen of the United States, residing at Masonville, in the county of Burlington and State of New Jersey, have invented certain new and useful Improvements in Signal-Lanterns, of which the following is a specification.

This invention relates to certain new and useful improvements in lanterns such as employed for railroad signaling and similar purposes, of which the following is a full, clear, and exact description.

The object of this invention is to provide a lantern having a novel globe-frame, wick-raising device, air-chamber, and burner attachment.

A further object of this invention is to provide a device which will be comparatively cheap and simple to manufacture, strong and durable, and highly efficient in its use and purpose.

Reference will be had to the accompanying drawings, forming a part of this specification, and wherein like numerals of reference designate corresponding parts throughout the several views, in which—

Figure 1 is an elevation showing the body proper in vertical section. Fig. 2 is a top plan view of the body, showing only half thereof. Fig. 3 is a vertical section of the burner and a portion of the oil-cup. Fig. 4 is a view in elevation of a fragment of one of the frame-sections, showing the manner of constructing the same. Fig. 5 is an elevation of half of the oil-cup, illustrating a modified form of the wick-raising device; and Fig. 6 is a top plan view of a fragment of the oil-cup.

Reference-numeral 1 designates the oil-cup of this lantern, to which is secured a base 2 and rim 3, formed with an upturned flange 4. Mounted in said flange is a cup 5, which forms a globe-support and has its bottom 6 perforated, as at 7, and formed on its lower face with lugs 8, which rest on the rim 3, forming an air-chamber between said rim 3 and bottom 6. The upturned flange 4 is formed with circumferential perforations 9, through which air enters said air-chamber and passes therefrom into the combustion-chamber through said ports 7. For securing the cup 5 within the flange 4 of the rim 3 a hook-shaped member 10, attached to the flange 4 and

adapted to engage lug 11, is provided on one side of the lamp, and coacting therewith is a spring-catch 12, secured to the rim 3 and having its upper end provided with a lug 13, entering recess 14 in the cup 5.

The globe-guard comprises a wire frame made from one continuous piece or in sections, each being formed from a piece of wire doubled to form loops 15 at its upper and lower ends. After the said loops are so formed the ends of the wire are brought to a point approximately central of the section and one bent in one direction and the other in the opposite direction, as designated by numerals 16 and 17, respectively. The sections after being assembled have the abutting ends of their lateral extensions 16 and 17, mentioned, connected by metal sleeves 18. It will be noted that the portion 19 and 20 of each section are so arranged that but one thickness of wire is in a radial line with the burner, so as to obstruct as little light as possible. Through the upper loops 15 of the globe guard or frame is passed a wire ring 21, to which the dome 22 is hinged by member 23, and the said dome is held in position by a spring-catch 24 of the usual type. The said cup 5 is formed in its upper portion with apertures 25, through which the lower looped ends of the guard are inserted and so secured by a wire ring 26, passing through the loops in the same manner as the upper ring 21 passes through the upper loops.

The burner-tube 27 passes through the burner-casing 28 through a slot 29 in the top of the oil-cup 1 and is formed with openings through which project wick-raising wheels 30 on shaft 31. Arranged in a circumferential groove in the burner-casing 28 is a loose collar 32, having a milled edge, whereby the same is rotated to engage the threads of its outer face with interior threads on a collar 34, secured to the oil-cup 1, the burner proper being prevented from rotating by the walls of the slot 29 engaging with the burner-tube 27.

Projecting through a tubular bearing 35 in the cup 5 is a second shaft 36, formed on its end with a head 37, removably received in a socket 38 on the outer face of a disk 39 on first-named shaft 31. The shaft 36 is normally pressed outwardly by a spring 40, arranged thereon between thumb-piece 41 and cup 5. When the shaft is pressed inwardly,

as shown in Fig. 2, so that head 37 enters socket 38, the wick may be regulated upon rotation of thumb-piece 41.

In the modification, Fig. 5, instead of the shaft for operating the wick-shaft being passed through the cup 5 it is arranged in a tubular bearing 45 on the oil-cup 1 and is provided with a gear 42, which may be brought into mesh with the wick-raising-shaft gear 43, as shown in said view, though normally the two gears are disconnected by the pressure of spring 44 between said tube 45 and thumb-piece 46.

In practice when it is desired to replace a globe the dome 22 is released by catch 24 and swung upon its hinge 23. When the lamp is to be filled, cleaned, or lighted, the cup 5 is detached from the oil-cup rim 3 by catch 12, and when it is desired to remove the burner the ring 32 is unscrewed from cup-ring 34, this removal being unobstructed by the wick-raising shafts, as they are normally out of engagement with each other. 47 is an opening in cup 5, forming a place to insert a match to strike it and light wick.

It is not the intention that this invention be limited to the details of construction set up, as various changes may be made without departing from the spirit or scope of the invention.

Having fully described the invention, what is claimed as new and useful, and desired to be secured by Letters Patent of the United States, is—

1. In a lantern, a frame comprising sections, each section formed of a single piece of wire doubled to form vertical members and the ends being bent on opposite sides thereof and joined to the adjacent end of the adjacent section.

2. In a lantern, a frame comprising sections, each section formed of a single piece of wire bent to form a vertical member, the ends of each section being bent at right angles to said vertical member on opposite sides thereof and joined to the corresponding end of the adjacent section. 45

3. In a lantern, a frame comprising a wire bent to form vertical members, the ends of each of said vertical members being bent substantially at right angles thereto to form a medial ring. 50

4. In a lantern, a frame comprising a wire bent to form an inner vertical member, the upper end of said wire being bent downwardly and at right angles to the vertical member on one side thereof, and the lower end being bent upwardly and at right angles to the vertical member on the opposite side thereof. 55

5. In a lantern, an oil-cup, a rim surrounding the same, a peripheral upturned perforated flange thereon, a cup formed with a concentric opening permitting it to be slipped over said oil-cup, said cup fitting within the 65 said upturned flange and being perforated, said cup being spaced from said rim thereby forming an air-chamber therebetween.

6. In a lantern, an oil-cup provided with a slot, a screw-ring on said oil-cup, a burner, a 70 wick-tube, a screw-collar loosely carried by and rotatable on the burner for engagement with the screw-ring, said wick being arranged within said slot.

In testimony whereof I affix my signature 75 in presence of two witnesses.

WILLIAM A. WRIGHT.
